CHEST OR SIMILAR ARTICLE

Bert J. Klein and Andre Bus, Altavista, and John B. Thorn,
Lynchburg, Va., assignors to The Lane Company, Inc.,
Altavista, Va., a corporation of Virginia

Filed Apr. 19, 1965, Ser. No. 84,863

Term of patent 14 years

(Cl. D33—6)

The figure is a perspective view of a chest or similar article, in the form of a chest on chest, embodying our new design.

In the figure, the side not shown is like the side shown while the back of the article of furniture is plain and unornamented.

We claim:

The ornamental design for a chest or similar article, as shown and described.
